UNITED STATES PATENT OFFICE.

JOHN BIRNIE, JR., OF BIRNIE, MANITOBA, CANADA.

MAIL-BAG CATCHER.

1,113,299.

Specification of Letters Patent.

Patented Oct. 13, 1914.

Application filed October 17, 1913. Serial No. 795,718.

To all whom it may concern:

Be it known that I, JOHN BIRNIE, Jr., of the town of Birnie, Province of Manitoba, Canada, have invented certain new and useful Improvements in Mail-Bag Catchers, of which the following is a specification.

My invention relates to improvements in mail bag catchers and relates more particularly to a mail receptacle mounted on the platform of a station, and the principal object of my invention is to design a box-like mail-bag catcher which will operate to strip the mail-bag or bags from the moving mail car whether the train is moving in a given direction or in a direction opposite to said given direction, provided it moves along a common track; in other words, my mail-bag catcher is constructed double ended.

Another object of my invention is to yieldingly support the means for stripping the mail-bags from the bag holder carried by the mail car so as to reduce to a minimum the danger of breaking the contents of the bag, and another object of my invention is to provide my mail bag catcher with a spring-controlled member mounted to be moved lengthwise thereof, so that when the mail-bags are discharged thereinto, they will strike this member and automatically release the trap door, which will lock one end of the receptacle closed, and, in its preferred form, my invention comprises a box-like receptacle open at both ends, which ends are preferably flared; a trap door hinged at each end of the receptacle and connected interiorly to a movable member mounted within the receptacle and held in normal position, by spring pressure; a yieldingly mounted stripping frame being mounted at each end of the receptacle and designed to detach or strip the mail-bags from their support on the mail car, as hereinafter more particularly set forth.

Figure 1 is a plan view of my mail-bag catcher showing the same positioned at the side of a platform. This view also shows portion of a mail car in section, showing the supporting arm for the mail-bags projecting through the door thereof. Fig. 2 is a side elevation of my catcher, certain parts being broken away and shown in section, to illustrate internal construction. Fig. 3 is, in part, a longitudinal section on the line 3—3, Fig. 1, and Fig. 4 is a vertical longitudinal section through the closed end of a modified form of my invention.

In the drawings, like characters of reference indicate corresponding parts in each figure.

My mail-bag catcher comprises a box-like receptacle A which is preferably mounted on a suitable support B, carried by the station platform C. This support B supports the receptacle A which is designed to contain the mail-bags, above the top of the platform C so that the mail matter will not be affected by dampness. Each end of said receptacle A is normally open, and the side and bottom walls D and E of said ends flare outwardly as illustrated so as to facilitate the entry of the mail-bags into the receptacle.

F are trap doors secured by the hinges G to the receptacle A, and by any suitable spring lock, hereinafter mentioned, the said trap doors are locked in open position. Positioned within the receptacle A is a member H, which separates the receptacle A into compartments I and J.

K are a plurality of rods, positioned substantially at each corner of the member H and passing therethrough, and these rods are supported at their ends within the receptacle A by any suitable means, such as blocks L secured within said receptacle and near each end thereof. Mounted on each rod K are two coiled springs M, one on each side of the member H, and extending from said member to said blocks L.

Without further description it will be understood that the member H is normally held in the position illustrated, particularly in Fig. 2, and should more pressure be applied against one side of said member than against the other, said member will be moved in the direction in which the greater force is applied, and when the pressure against said member is removed, the said springs M under compression will force it back to normal position. When the mail-bags are stripped from the supporting arm N which projects through the door O of the mail car P, they possess a considerable amount of momentum, and as a result of this momentum, the said mail-bags, for instance the mail-bag Q, will be thrown into the compartment I, and against the member H. This member will immediately yield and so reduce to a minimum, danger of injuring the contents of the mail-bag. Not only does the member H perform the function of reducing to a minimum the impact of the mail-bag Q thereagainst, but it also performs the additional

function of releasing the trap door R of the compartment I so that this trap door will be closed by gravity, and by means of the spring lock S, lock this compartment. Carried by the member H, and at each side thereof, are flexible members 2. These flexible members are each attached to said member by any suitable means, such as eyelets 3, and the other end of each of the said flexible members is connected to a spring-provided bolt 4, of the spring-locks 5, which locks are suitably secured to the top 6 of the receptacle A and at each end thereof. The outer end of each bolt 4 is normally held in a plate 7 carried by the trap doors F. Now when said member H is moved as described, the bolt 4 of the trap door R is disengaged from its plate 7, thus permitting this trap door to close, as described. Although only one spring-lock 5 and its connected parts is illustrated in Fig. 1, it will be understood that each trap door F is provided with one of these spring locks, and preferably two.

As before mentioned, a stripping frame is mounted before each end of the receptacle A. My preferred form of stripping frame comprises a stripping bar 8, preferably curved inward, as illustrated in Fig. 1, and preferably formed integrally with each end of said stripping bar is an arm or lever 9. Each arm or lever 9 is pivoted at its lower end by a pin or rivet 10 in a bracket 11 carried by the platform C. Carried by each arm or lever 9 is a bracket 12. Associated with each arm or lever 9 is a stay-rod 13, and the upper end of each stay-rod is pivoted to its associated bracket 12 by a pin or rivet 14 held in the upper end thereof. The lower end of each stay-rod extends through the top plate 15 of a bracket 16 carried by the platform, and mounted on this lower end is a coiled spring 17, which is retained thereon by a pin 18. As illustrated by dotted lines in Fig. 1, the slot 19 formed in the plate 15 of each bracket 16 is shaped to allow for the proper movement of each stay-rod 13. The normal position of each stripping frame and their stay-rods, is illustrated very clearly in Fig. 2. It will be noticed in this figure that the stripping-bar 8 of each stripping-frame is positioned well above the trap doors F, and in Fig. 1, I illustrate the fact that the arms or levers 9 are positioned beyond the side walls D. Therefore at no time will the said stripping frames conflict with the receptacle A.

The mail car P, carrying the supporting arm N, is supposed to be moving in the direction indicated by arrow in Fig. 2, and the dotted position of said supporting arm in this figure illustrates the position of the outer end of this arm, and a mail-bag carried thereby, before the mail-bag strikes against the stripping bar 8. The impact of the mail-bag against said stripping-bar will

result in the removal of the said bag from the arm N, and the tossing of the same into the compartment I, as already described.

The supporting arm N is illustrated in full lines in the Fig. 1 merely to illustrate the position of the outer end of this arm in respect of the stripping bars 8 so as to show that the mail-bags will be supported in the most advantageous position for the stripping frames. Of course the receptacle A can be made weather proof and constructed strong enough to protect the mail matter therein under normal conditions.

It will be understood that I may construct my mail-bag catcher so that it will only possess one compartment, and consequently only receive the mail-bag through one end. This will be understood upon referring to Fig. 4. The receptacle A' may be provided with a permanently closed end a, and the member H, while mounted upon the rods K' will be cushioned against the springs M', which rest against the blocks L' so that this member may perform the function already described.

Where mail matter is immediately removed from the receptacle A, the trap doors F may be omitted. The arms or levers 9 are separated by a wide space so as to insure no interference on the part of the stripping frame with the passage of the mail-bags into a receptacle.

Various changes in construction may be made without departing from the scope of my invention, as set forth in the appended claims.

The stripping bar 8 is curved as illustrated in Fig. 1 so that the deepest part of the curve will be substantially mid-way its ends. When the stripping frame is mounted for use, the said stripping bar will be positioned so that the middle thereof will be on a line with the longitudinal axis of the receptacle A. So curving the said stripping bar has a tendency to compel the mail bag to be centralized in its path of movement in respect of the open end of said receptacle so that it will be thrown thereinto without conflicting with the sides thereof.

What I claim as my invention is:

1. A mail-bag catcher comprising a receptacle each end of which is normally open; a partition positioned within said receptacle and vertically disposed, to divide the same into two compartments; a plurality of straight rods positioned within said receptacle to extend in substantially parallel relationship longitudinally thereof and passing through said partition one at each corner thereof; means mounted within each of the said compartments whereby the outer ends of said rods are supported; a coil spring mounted on each of the said rods in each of the said compartments on each side

of the said partition with their inner ends abutting against the said partitions and their outer ends abutting against the supporting means for the outer ends of said rods; a trap door hinged at each end of said receptacle; means for latching said trap doors in open position, and a flexible connection for each of the said latching means attached to said partition near the upper portion thereof, as set forth.

2. A stripping frame for a mail-bag catcher comprising a substantially horizontal stripping bar which is curved inwardly so that the deepest point of the curve will be substantially mid-way the ends thereof; a lever connected with each end of said stripping bar and positioned substantially parallel to each other, and designed to normally occupy a position at an angle to the verti-

cal; a straight stay rod pivoted at its upper end to each of the said levers, each stay rod also normally occupying an angular position to the vertical; a slotted bracket for each of the said stay rods through which the lower ends thereof extend, and a coiled spring mounted on the lower end of each of the said stay rods below each of the said brackets and performing the function of providing a yielding support for said stripping bar and its supporting levers, as set forth.

In testimony whereof I have affixed my signature.

JOHN BIRNIE, JR.

In the presence of—

A. E. SERVANTÉ,
G. E. MONTGOMERY.
